UNITED STATES PATENT OFFICE.

BENJAMIN OTTO FANSLOW, OF LOS ANGELES, CALIFORNIA, ASSIGNOR, BY MESNE ASSIGNMENTS, TO POLYGRAPH DUPLICATING TYPEWRITER COMPANY, A CORPORATION OF NEW YORK.

MACHINE FOR SETTING AND DISTRIBUTING PRINTING-TYPE.

1,076,029.

Specification of Letters Patent.

Patented Oct. 21, 1913.

Application filed April 8, 1907. Serial No. 367,128.

To all whom it may concern:

Be it known that I, BENJAMIN OTTO FANSLOW, of the city of Los Angeles, in the county of Los Angeles, in the State of California, have invented a certain new and useful Machine for Setting and Distributing Printing-Type, of which the following is a full, clear, and exact specification, reference being had to the annexed drawings and to 10 the figures and letters marked thereon.

My said invention relates to a mechanical device for setting type from a type-container into a holder to be used in printing-machines of various kinds and for distributing the type from the type-holder into the type-container, after it has been used in printing operations.

The type-holder which I use is either of the kind shown in my application Serial No. 324,704, filed July 3, 1906, or I may use type-holders of other constructions hereinafter described, wherein the type may be slid in between the partitions thereof and through an open end of each division of the type- 25 container.

In the drawings: Figure 1 is a plan of the type-setting and type-distributing machine, constituting my present invention; Fig. 2 is a transverse section thereof on the line $x-x$, Fig. 1; Fig. 3 is a front end elevation of the machine looking in the direction of the arrow Z, Fig. 1; Fig. 4 is a longitudinal section of the machine, the central part of which is broken out of the figure and drawn on the line $x'-x'$, Fig. 1; Fig. 5 is an enlarged view showing the type-ejector in end elevation, the figure being broken in two to curtail the view; Fig. 6 is a transverse section on the line x^2-x^2 , Fig. 40 5; Fig. 7 is a side elevation of a detail of the machine on a larger scale than Fig. 1; Fig. 8 is a vertical section at right angles to Fig. 7; Fig. 9 is a perspective view on an enlarged scale showing a sliding index block 45 and portions of the index bar; Fig. 10 is a vertical section on an enlarged scale of one of the type-holders, showing one form of the type; Fig. 11 is a view similar to Fig. 10, showing a different form of some parts of 50 the type-holder but containing the same kind of type as in Fig. 10; Fig. 12 is a view similar to Fig. 10, showing parts of the type-holder and type on the same enlarged scale, the type being of another form; and

Fig. 13 is a plan of a printing-machine of 55 the kind described in my application Serial No. 363,810, filed March 18, 1907, and showing one of the type-holders, with the type and dividing-blocks set therein, in readiness for use.

The machine constituting my invention and shown in Figs. 1, 2, 3 and 4 is therein shown operating as a type-setting machine. The machine consists of the rectangular base A, preferably formed of cast-iron. At the 60 bottom of this base A, there are two grooved rails B and B', in the grooves of which anti-friction rollers C are placed and operate. Upon the anti-friction rollers C, C, there is carried the type-container D, consisting of 65 a rectangular frame having a series of parallel strips E therein, in the spaces between which strips the types F are carried. The front part of this type-container D is provided with a handle G, by which the operator may slide the container D backward and forward upon the rails B and B'. For the purposes of holding the type-container D in place and preventing it from leaving the anti-friction rollers C, C, a rod H, preferably circular, having a milled head H', passes through a hole in the front end of the base A, as shown in section at Fig. 4, in plan at Fig. 1 and in transverse section at Fig. 2. The opposite end of the rod H is formed 70 with a screw-thread H², which enters a corresponding screw-threaded hole in the rear end of the base A, so that on turning the rod H, when passed through the hole in the front end H of the base A, and through corresponding holes in the lugs H³, on the bottom of the type-container, the latter is held in proper operative position. The outer or 75 left-hand edge of the type-container D is constructed with a rack-bar I, which gears with a pinion J, as shown at Figs. 2 and 3, upon the base of a vertical shaft K, (carried in bearings K', K', of a vertical bracket 1) at the upper end of which is a bevel-pinion L, Fig. 2, gearing into another bevel-pinion M, upon the screw-shaft N, journaled at one end in the bracket 1 and at its other end in the bracket 2, extending vertically from the opposite side of the frame A.

When the type-container D is moved by 105 pulling or pushing upon the handle G, then the toothed-rack I causes the rotation, in one or the other direction, of the pinion J, the

shaft K, the bevel-pinion L, the bevel-pinion M, and, consequently, the screw-shaft N. As the shaft N is thus rotated in either direction, so the sliding index block O is moved transversely, said block being screw-threaded upon said shaft and having overlapping lugs O', engaging the face of the guide-bar P, which thus prevents block O from turning on the shaft N, the screw-threaded connection, however, causing said block to travel longitudinally of the shaft. The front of the guide-bar P has thereon the letters of the alphabet, numerals, punctuation, brackets, dashes and other symbols used in the art of printing, as shown at Fig. 3, from which it follows that the user of the machine, in moving the type-container on the rails B and B', Fig. 1, stops the type-container at the desired position indicated by the index-block.

The type-holder Q is supported on the rails R, which are V-shaped in cross-section and project from the bottom of the frame A parallel with bars B, the holder Q having projections R' on the bottom, as shown at Fig. 2, and which type-holder is maintained in its proper relationship to the rest of the machine by the rod H⁶, having a milled head H⁶, and its opposite end having a screw-thread thereon entering and screwing tightly into a corresponding hole in the other end of the frame. By this means the type-holder is maintained in a sufficiently easy, slidable and sufficiently rigid position on the rails R, so as to be capable of horizontal movement thereon from time to time whenever a line of type has been completely set, and the next line of type has to be set, in which case the type-holder Q is moved forward one space, or more than one space, as the case may require, beneath the bar P, so as to receive the next line of type delivered thereinto from the type-container D. The pitch of the screw N is so proportioned in relation to the rack I, of the type-container D, and pinion J, that it is capable, by its rotation, of moving the index-block or pointer O in either direction along the entire length of the rod P by a complete movement or travel of the rack of the type-container. The adjacent sides of the container and holder are open, as shown in Figs. 1 and 2.

The type-holder Q is maintained in any position required during the receiving of type from the container D by means of the teeth S, on the upper edge of the side-bar of the frame A, with which cooperates a spring-operated pin T, Figs. 7 and 8, carried by the type-holder, and which engages with the recesses between the teeth S, said pin being pressed downward by the spring T', of the lug T², projecting from the adjacent side of the holder.

65 In order to eject the type, represented by

the squares in the grooves of the type-container D, Fig. 1, and also represented in end elevation in Fig. 3, there is contained between the pair of bars U, pivotally connected to the links X, X^a, Figs. 1 and 3, a series of inclined elastic strikers or fingers V, which are held firmly between the bars U, U, so that, by giving a slight horizontal movement to these elastic strikers, the lower ends of which are in contact with the heads of the types F, Figs. 1 and 3, it follows that each successive forward movement, of the elastic strikers or fingers V, pushes one of the types F, at the end of each groove in the type-container D, out of said groove and into the corresponding groove of the type-holder Q, wherein type is being set.

The bars U of the ejector are pivotally carried by the links X, X^a which, in turn, are pivoted at opposite sides of the frame on brackets 1 and 2, respectively, just below the guide-bar P, the ejector being thus capable of swinging longitudinally across the frame and the container and holder. The vertical rod X', sliding in bearings X³, extending from bracket 2, Fig. 3, is provided with a touch-arm X², as shown in Figs. 1 and 3, and by placing a finger thereon the rod X' is depressed in its bearings, while the coiled spring X⁴, connected to the rod X' at one end and to the pin 3 at its other end, is distended. The upper end or head of the rod X' operates against the edge of the link X^a, which is in the form of a cam, as shown at Fig. 3, and this edge of the link X^a is pressed against the upper end of the rod X', by means of the spring X⁵, at the opposite side of the machine, which bears against the link X. The pressure from the spring X⁵ is transmitted, through the rods U, to the other link X^a, in contact with the upper end of the sliding-rod X'. From this arrangement it follows that, by depressing the sliding-rod X', the coiled spring X⁴ is stretched as shown at Fig. 3 and the head of the vertical rod X' is moved along the edge of the link X^a, correspondingly causing transverse movement of the bars U and of the fingers or strikers V, while simultaneously pressing rearward the spring X⁵, which spring instantly reacts when the finger of the operator is lifted from the arm X², and instantly causes the fingers or strikers V to be moved horizontally and sufficiently far in the opposite direction to eject a type from the type-container D into the corresponding groove in the type-holder Q.

Instead of using separate strikers or fingers V, as shown at Fig. 3, I may use a continuous bar b, of elastic india rubber serrated on opposite edges, but the teeth of which point in opposite directions, as shown in Figs. 5 and 6.

With regard to the forms of type which I use in the machine, the forms vary according to the shape, dimensions and form of the holding-devices in or upon the vertical division between each pair of rows of the type-holder. For example, in Fig. 10, the bottom of the type-holder is that which is marked *c*, in which the vertical strips of metal *d*, *d*, are fastened, and the top of each of the vertical strips of metal *d*, is formed or provided with approximately diamond-shaped strips of metal *e*, extending the entire length thereof. The types *f*, used in the type-holder of the construction shown at Fig. 10, each have a recess at opposite sides so as to fit snugly on and between the strips *e*. When the kind of type-holder is used as shown on the enlarged scale in Fig. 10, then the bottom of each type *f* does not touch the upper part of the base *c* of the type-holder, but the type is supported entirely by the projecting-strips *e*, at the head of each partition *d*.

In the type-holder shown in Fig. 11, the divisions *d* are the same as the corresponding divisons in Fig. 10 and each of the divisions *d* carries at its top a circular strip *e'*, instead of the diamond-shaped strip *e*, as shown at Fig. 10. The structure of the type and its mode of suspension are the same as in Fig. 10.

In Fig. 12, the type-holder is shown as consisting of the same flat bottom-plate *c*, but the partitions *d* extend to a greater height, namely, to nearly the top of each type *f*, while the top of each partition *d* is constructed with a V-shaped ridge or flange, as shown at Fig. 12. When the types *f* are slid into the type-holder shown at Fig. 12, the bottom of each type *f* rests solidly upon the top surface of the bottom *c*, of the type-holder, and is also held at the upper part of the V-shaped flange *e*, as shown. This arrangement provides for holding the type very rigidly in the type-holder, said type having their coöperating edges slabbed off for coöperation with the flange *e*.

Whatever the form of the type used in my type-setting and type-distributing machine, the type-container and the type-holder have the spacing-bars thereof correspondingly formed.

Fig. 13 is a plan of an inking-ribbon printing-machine of the type for which I have applied for Letters Patent, as aforesaid, and showing the type-holder *Q* used therein corresponding with the type-holder and type partly set therein, shown in plan at Fig. 1.

From the foregoing description of the details of my invention, the following mode of operation will be readily understood: The type-holder and container having been set in place and secured by means of the rods

*H*⁴ and *H*, respectively, and the type-holder having been located in the position on the frame desired, the spring-pint *T* will retain such location until it is desired to move the holder for the introduction of additional rows of type. The type-container will then be moved back and forth on its guides, in accordance with the particular type characters which it is desired to eject therefrom into the holder, by manipulating the container by the handle *G*. Movement of the container longitudinally of the frame results in rotating the vertical shaft *K* and, through the connecting gearing, the cross-shaft *N*, the pointer or index-block *Q*, at the same time, being caused to move longitudinally of the guide-bar *P*. The operator keeps his eye upon the said guide-bar and, consequently, is enabled to determine just when to stop the container, because of the registration of the index-portions *O'* of the block *O* with the particular character desired to be ejected from the container. As soon as the indicator shows the proper character to be under the ejector, the operator depresses the arm *X*², which causes the head of the rod *X'* to engage the cam-link *X*^a and push the ejector-bar *U* to the left, Figs. 1 and 3, thus placing the springs *X*³ and *X*⁴ under tension. By releasing the arm *X*², the spring *X*⁴ immediately retracts the rod *X'* and the spring *X*³ immediately shifts the ejector, causing the elastic fingers to move the row of type with which it is registered and shift a single type from the confainer into the holder. This operation is continued until an entire line of type is set up in the holder, the types being moved along in the holder by the successive types shifted thereinto. As each line of type is completed in the holder, the latter is moved along so that the lines of type in the container, from end to end thereof, can be made to register as desired with the channels between the bars in the holder where the type is being set. When the type-holder has been completely filled, it is removed from the machine by removing the rod *H*⁵, which permits said holder to be lifted from the frame when it can be set in the machine for reproduction, as shown in Fig. 13, this figure illustrating the polygraph or reproducing machine shown in my aforesaid application.

After type has been set in the machine and reproduced, as just described, the next operation is to distribute the type from the type-holder into the type-container. This is effected by removing the type-holder *Q* from the printing-machine and replacing it upon the rails *R* of the frame *A*, and fastening the type-holder with the type set therein by inserting the rod *H*⁶, into the hole in the base *A*, passing the rod through the lug in the bottom of the type-holder, and then screwing the outer end of the rod *H*⁶ into its

correspondingly tapped hole in the rear end of the base A. The bars U, containing the strikers or fingers V, are now reversed in their position; that is to say, the two retaining-bolts W, shown at Fig. 5, are removed and the bars U turned around so that the strikers or fingers, or serrations, which are uppermost in Fig. 5, become reversed, so that when the arm X² is depressed by the finger of the operator the strikers or serrations, operating in the opposite direction, force the types out of the holder into the proper rows or spaces in the type-container, and this series of operations is continued until the whole of the types, contained in the type-holder, are distributed in the type-container D and ready for being reset according to other copy, it being understood that, after the bars U, containing the strikers or fingers V, are reversed, then the bolts W are replaced in the holes by which the bars U are connected to the links X, X^a.

Having thus described my invention, what I claim and desire to secure by Letters Patent is:

1. In combination, a flat type-case mounted to move longitudinally and having transverse guideways for holding types, a movable chase held removable adjacent to the said type-case and having guideways, any one of which may be moved in register with the said type-case, and means for shifting the type from one registering guideway into the other.
2. A type setting and distributing machine provided with a removable receiver having guideways for the reception and retention of the type, and a movable flat type-case having spaced parallel guideways for holding type, the guideways of the receiver and the guideways of the type-case being adapted to be moved in register one with the other to transfer type from one guideway to the other.
3. A type setting and distributing machine, consisting of a supporting-frame; guide-bars carried by said frame within its confines and extending longitudinally thereof; a type-container having one side open; a type-holder having one side open; the container and holder being arranged side by side within the confines of said frame and having their open sides next to each other; means on the frame, container and holder coöperating to retain the container and holder on the frame in movable relation; means for holding the holder stationary during the operation of the container; means by which the container may be moved relatively to the holder; and means for ejecting type from one to the other of said container or holder.
4. In combination with a flat frame, a type-container and a type-holder, the same being arranged in the frame in parallelism

and capable of moving relatively to each other; means for retaining the holder stationary while the container is in operation; means by which to manipulate the container relatively to the holder; and said container being provided with a rack-bar, a rotatable shaft journaled in bearings on the frame and extending transversely across the latter above the container and holder, an index-block carried by said shaft, and means between the latter and the rack on the container for rotating the shaft as the container is moved relatively to the holder whereby the index-block will be moved along the shaft; and an index-bar coöperating with the index-block to prevent the latter from turning with the shaft.

5. In combination with the type-holder and type-container, a type-setting and a type-distributing mechanism comprising a horizontal bar, means for pivotally supporting the bar, means carried by the bar for engaging the type to eject the same from one to the other of the container or holder, means whereby the bar may be reversed so as to operate in opposite directions, and means whereby the said bar may be actuated, substantially as described.

6. In combination with a type-holder and type-container, a type-setting and distributing mechanism comprising a pivotally-supported bar carrying strikers for engagement with the type in the container or holder, means whereby the bar may be reciprocated relatively to the holder and container, said means including a reciprocating rod and coöperating cam at one end of the bar, and a spring coöperating with the other end of the bar to reverse the movement of the latter which is imparted thereto by the rod and cam.

7. In combination with a type-container and type-holder, means for ejecting type from one into the other of the container or holder, said means comprising a bar carrying a plurality of flexible, inclined strikers for coöperation with the type in the container and holder, and means for actuating the bar to cause the strikers to move the type.

8. A type-setting and distributing machine comprising a hollow, rectangular frame provided with a plurality of longitudinal supporting-bars on the bottom thereof; a type-container having means for coöperating with certain of said bars; a type-holder having means for coöperating with the others of said bars, both the container and the holder having an open side and said open sides being arranged next to each other; means for removably securing the holder and container in the frame with freedom to move relatively to each other and to the frame; means operating transversely of the holder and container whereby type may be shifted from one to the other

through the open sides thereof; and means whereby the container may be moved relatively to the holder.

9. A type-setting and distributing machine having, in combination, a supporting-base, a type-container, means between the container and base for supporting and guiding the former, a rod extended transversely of the base above the container, an index carried by the rod, means between the rod and index whereby rotation of the rod will cause longitudinal movement of the index thereon, and means between the rod and the container for rotating the rod.
10. A type-setting and distributing machine having, in combination, a holding-frame, a type-container slidably supported on said frame, a type-holder slidably supported on said frame in coöperative rela-

tion to the container, a type-ejector supported above the holder and container, means whereby said ejector may be reciprocated relatively to the container and holder, a rod supported in parallelism with the ejector above the holder and container, an index-block carried by the rod, and means for causing the index-block to move proportionately with the movement imparted to the container.

In testimony whereof, I have hereunto set my hand and seal at the city of Los Angeles aforesaid, in the presence of two subscribing witnesses.
